[57] CLAIM

The ornamental design for a modular cabinet, as shown.

DESCRIPTION

FIG. 1 is a perspective view of a modular cabinet showing my new design;
FIG. 2 is a front elevational view thereof;
FIG. 3 is a left side elevational view thereof;
FIG. 4 is a rear elevational view thereof;
FIG. 5 is a top plan view thereof;
FIG. 6 is a perspective view of a second embodiment of the modular cabinet shown FIG. 1;
FIG. 7 is a rear perspective view thereof;
FIG. 8 is a side elevational view thereof;
FIG. 9 is a top plan view thereof;
FIG. 10 is a front elevational view of a third embodiment of the modular cabinet shown in FIG. 1;
FIG. 11 is a rear elevational view thereof;
FIG. 12 is a side elevational view thereof;
FIG. 13 is a front perspective view thereof; and
FIG. 14 is a rear perspective view thereof.
